UNITED STATES PATENT OFFICE.

MICHAEL WOODS AND THOMAS JEFFERSON GILBERT, OF BRUNSWICK,
VICTORIA, AUSTRALIA.

PORTABLE APPARATUS FOR DRESSING THE SURFACES OF RAILS IN SITU.

SPECIFICATION forming part of Letters Patent No. 795,184, dated July 18, 1905.

Application filed September 27, 1904. Serial No. 226,211.

To all whom it may concern:

Be it known that we, MICHAEL WOODS, residing at 309 Pigdon street, Princes Hill, Carlton, and THOMAS JEFFERSON GILBERT, residing at 1 Minnie street, Brunswick, in the county of Bourke, State of Victoria, and Commonwealth of Australia, subjects of the King of Great Britain and Ireland, have invented certain new and useful Improvements in Portable Apparatus for Dressing the Surfaces of Rails in Situ, of which the following is a specification.

The object of our invention is to provide an apparatus for cheaply and expeditiously removing joint or other inequalities in the surfaces of tram or other rails while they are in place. In the past, especially where rails were uneven at the joint, it has frequently been the practice to remove the unevenness or inequalities by chipping or filing; but with our invention a rotating dressing-wheel which is mounted on a portable framework is provided. One end of the said framework is capable of being elevated or depressed. The said framework can also be moved by hand along the rails, and the dressing-wheel and its shaft are capable of moving longitudinally. The framework can also be bodily elevated by a crank and lever, and thus, like a two-wheeled hand-truck, be ready for transport to any distance from the rails.

Referring to the drawings which form a part of this specification, Figure 1 represents a perspective view of our invention, showing the framework above a rail to be dressed, the flange of one of the front wheels and a vertically-adjustable rear wheel being in the rail-groove. The said rear wheel has been depressed, thereby elevating the rear end of the framework and the dressing-wheel. Fig. 2 depicts a side perspective view of the front of the apparatus, showing the gear by which the framework is traveled along the rail. Fig. 3 shows a perspective view looked at from the rear end of the apparatus. The rear end of the framework is elevated. Being overloaded, the front end of the framework rests upon the front wheels. The framework is bodily elevated by the crank and transport wheels. Fig. 4 depicts an end view of the

intermediately-pivoted hand-lever, whereby the dressing-wheel shaft is moved longitudinally.

Similar letters of reference indicate similar or corresponding parts where they occur in the several views.

Our invention includes a portable framework having a front end A and a rear end B. The said framework can be of any section and preferably has welded corners. Beneath its front end are two front wheels C, one or both of which may be singly or doubly flanged. Beneath the rear end is a rear wheel D. This is provided with a single or double flange and turns upon a stud E, protruding from the bottom of a vertical slide F. The upper portion of this slide F moves in a guide G, attached to the framework, and the top of the said slide has connected thereto the lower end of an elevating or depressing screw H. This turns within a nut attached to a bracket J, and its upper end has attached thereto the elevating or depressing hand-wheel K.

Near the hand-wheel K is the traveling hand-wheel L. This turns a shaft M, on the front end of which is a bevel-wheel N. This bevel-wheel N engages with another bevel-wheel O, attached to the top of the down-shaft P. At the bottom of the said shaft P is fixed a bevel-wheel P'. This engages with another bevel-wheel (not shown) fixed upon the live axle Q and supporting the front wheels C, or the down-shaft P may be dispensed with and the front end of the shaft M lead to the bevel-wheel upon the axle Q.

Upon the front end of the framework is situated an oil or other motor R. This obtains its fuel from the oil-tank S and its jacket-circulating water from the water-tank T. It may be started by a crank-handle O'.

On the motor-shaft is the driving-pulley U, from which a belt V drives the pulley W upon the dressing-wheel shaft X. This shaft X turns within bearings attached to the rear end of the framework, and on an overhanging portion of the said shaft X is attached the dressing-wheel Y. The said shaft X is capable of a longitudinal movement within its bearings. Around the said shaft is a circumferential groove or a groove formed by col-

lars V', in which groove the lower portion of the legs S' of a forked hand-lever Z engage. The said hand-lever, which moves in the same plane as the axis of the shaft, is intermediate pivoted at Q' to the framework or stay R' or other part. At its upper end it is provided with a bell-cranned spring-pawl A', which engages in a rack B', secured to the framework or the standard J.

10 To the framework and near its middle are attached two crank-pin bearings C'. In these turn the crank-pin D'. At each end of the crank-pin are the inner ends of crank-legs E'. At the outer or lower ends of the said crank-legs are crank-axes F'. Upon these turn the transport-wheels G'. To the crank-pin D' is attached the inner ends of combination elevating pulling or pushing levers H'. The outer ends of the said levers are united by a cross-bar J'.

To the framework is attached the lower end of a spring-catch K'. The upper end L' of this is bent backwardly upon itself, forming a stop M'. In Fig. 3 the combination-lever H' is retained by the stop, which stop when it is pulled outwardly from the lever releases the same.

Below the rear end of the framework is a dust-shield N'. A dust-shield may also be 30 placed above the pulley W.

The cycle of operations with our invention is as follows: When the apparatus requires transporting, the cross-bar J' is depressed until the lever H' passes beneath the stop M'.

35 The body of the framework is thereby lifted. Since the front end of the apparatus is slightly heavier than the back end, the front wheels rest upon the ground. The operators lift the cross-bar J' and push the apparatus along the 40 road on the two transport-wheels till the rail to be dressed is reached. The spring-catch is then pulled outwardly and the cross-bar J' rises and the flanges of the rear and front wheels are dropped into the groove. The 45 motor is then started and the hand-wheel K turned until the dressing-wheel Y bears upon the portion to be ground. The hand-wheel L is then turned and the framework moved backward and forward, as desired. The dressing-wheel can also be moved sidewise by 50 means of the hand-lever Z. This dressing-wheel Y is preferably of such nature as to grind the surfaces to which it is applied. It will of course be obvious, however, that, if 55 preferred, a milling-wheel may be used.

Having now described our invention, what we claim as new, and desire to secure by Letters Patent, is—

1. An apparatus of the character described, 60 comprising a movable frame, means for adjusting the frame vertically, and a dressing-wheel supported by the frame and vertically and laterally adjustable thereon.

2. An apparatus of the character described, comprising a movable frame, means for independently adjusting the ends of the frame vertically, and a dressing-wheel supported by the frame and vertically and laterally adjustable thereon. 65

3. An apparatus of the character described, 70 comprising a movable frame, means for independently adjusting the ends of the frame vertically, a dressing-wheel supported by the frame, and means for adjusting said wheel laterally and vertically independently of the 75 frame.

4. An apparatus of the character described, comprising a frame having propelling means thereon, independently-operated means for vertically adjusting the frame, a dressing-wheel supported by the frame, and means for adjusting said device in relation to the frame, and vertically and laterally adjustable thereon. 80

5. An apparatus of the character described, comprising a frame having propelling means 85 thereon, independently-operated means for vertically adjusting the frame, a dressing device supported by the frame, and independent means for adjusting the device vertically and laterally independently of the frame. 90

6. In a portable apparatus of the character described, the combination with transport-wheels and a crank-axe supported thereby; of a framework mounted upon the axle, an operating-lever extending from the axle, an 95 elevating mechanism extending from the framework at one end, and a dressing-wheel adjustably connected to the frame.

7. In an apparatus of the character described, the combination with a framework; 100 of a vertically-adjustable slide at one end of the framework, a wheel mounted upon the slide, means for operating the slide, a dressing-wheel rotatably mounted upon the framework, means for adjusting the wheel laterally, 105 and a locking device for said adjusting means.

8. In an apparatus of the character described, the combination with a crank-axe and transport-wheels mounted thereon, of a framework supported by the axle, means for rotating the axle, a holding device for said means, wheels connected to opposite ends of the frame, propelling mechanism for rotating the wheel at one end, vertically-adjustable means connecting the other wheel with the frame, a 115 dressing device connected to the frame, and mechanism for vertically and laterally adjusting said device.

In witness whereof we have hereunto set our hands to this specification in the presence of 120 two witnesses.

MICHAEL WOODS.

THOMAS JEFFERSON GILBERT.
